UNITED STATES PATENT OFFICE.

RAY C. HALL, OF NEEDHAM, MASSACHUSETTS, ASSIGNOR TO FRANK W. GORSE CO., OF NEEDHAM HEIGHTS, MASSACHUSETTS, A CORPORATION OF MASSACHUSETTS.

SHORT-STRETCH COVERED ELASTIC THREAD.

Application filed February 28, 1927. Serial No. 171,673.

This invention relates to elastic covered rubber threads adapted to enter the construction of a wide variety of knitted and woven fabrics and garments.

One of the objects of this invention is the provision of an elastic covered rubber thread so constructed and arranged that the stretch or elongation of the rubber thread is limited and is held well below the elastic limit or 10 rupture point of the rubber thread.

In the manufacture of the ordinary form of covered rubber thread, some attempt has been made to limit the stretch of the covered rubber thread by greatly stretching the bare rubber thread and holding it in stretched condition while the covers, usually two in number, and each consisting of a plurality of threads or ends, are wound on tightly with close-pitched convolutions. This method 15 provides a short stretch elastic thread but the thread is always under a relatively heavy tension since the covers hold the thread from contracting and there is nothing to limit the stretch of the rubber thread but the resistance of the rubber thread itself so that if the rubber thread is stressed unduly it will 20 rupture. A fabric made of such elastic thread has a relatively short life since the rubber is always under a relatively heavy tension and is furthermore objectionable 25 since if the rubber thread is severed, as with a needle during the sewing of the fabric, the severed ends will pull away from each other due to the inherent great tension on the rubber thread and leave a gap in the fabric.

It has also been proposed to limit the stretch of the rubber by laying an inextensible, or stay, thread alongside the rubber thread, or twisting the two threads together, 30 and winding the covers thereon. The resultant product, however, assumes a cork-screw formation and is twisty or kinky and so has a poor appearance when compared with the straight usual covered rubber thread. It 35 is also difficult to cover the rubber and stay threads, to entirely conceal the rubber thread, under some conditions.

It is an object of this invention to provide a short, or limited, stretch, low-tension 40 covered elastic thread wherein the stretch of the rubber thread is limited by the characteristic of the covers alone and the manner in which the covers are applied.

A further object of the invention is the provision of a short-stretch, low-tension

covered elastic thread having such characteristics that it can be made in the usual covering machines, and will lie flat and straight and is free from kinks and loops or a cork-screw effect.

A further object is a novel method of covering an elastic rubber thread to provide a short-stretch low-tension covered rubber thread.

A yet further object is generally to improve covered elastic threads and methods of making them.

Fig. 1 is an enlarged representation of the covered thread embodying this invention with the superimposed covers being successively unwrapped to illustrate the character and arrangement of the covers.

Fig. 2 illustrates a section of the elastic rubber thread with the first cover applied thereon.

Fig. 3 is a view similar to Fig. 2 but showing the arrangement of the first and second covers.

Fig. 4 is a view similar to Fig. 2 but showing the application of the third cover 80 over the first two covers.

Fig. 5 is an enlarged view of the thread with the covers partially unwrapped and illustrating the manner in which the covers function to limit the stretch of the elastic rubber thread.

The elastic thread embodying this invention comprises an elastic rubber thread 10 on which are applied a plurality of superimposed spirally-wound textile cover threads 12, 14, 16 and 18. The innermost cover thread 12 is tightly wound onto the elastic rubber 10 in a relatively long-pitched or open spiral as is shown in exaggerated form in Fig. 2. The intermediate cover thread 14 is wound in the opposite direction over the first cover thread and the rubber thread and the convolutions thereof also have a long pitch, comparable with the pitch of the convolutions of the innermost winding 12, as illustrated in Fig. 3. The third layer 100 of cover thread 16 is wound about the two cover threads 13 and 14 oppositely to the cover 14, and has a shorter pitch spiral, or is more closely wound as illustrated in Fig. 4.

Each of the aforesaid covering layers 105 preferably comprises a single thread although for certain purposes the third cover may have more than one thread or "end."

The outermost cover 18 is composed of a 110

number of textile strands or threads layed side by side and as shown in Fig. 1 is composed of four strands or "ends." The outermost cover is wound about the other 5 layers in a short pitched spiral in a direction opposite to the direction of winding of the next lower cover 16 and, in cooperation with the under covers, completely conceals the elastic rubber thread. The cover-layers are wound on the elastic rubber thread in any usual or suitable covering machine and the covers are applied at the same time and in opposite directions so that the rubber thread is held without undue twisting.

15 The elastic rubber thread 10 is maintained under but a small amount of tension during the covering operation.

The two inner covers 12 and 14 serve primarily to limit the extent of stretch of 20 the rubber thread although the remaining covers also assist in limiting the stretch. As the covered rubber thread is elongated, the pitch of the spirals of the covers 12 and 14 are lengthened causing them to bite into 25 or compress and grip the rubber thread 10 as illustrated in Fig. 5, thereby restricting the stretch of the rubber by compressing it. The length of the covers 12 and 14 when substantially straight is adapted to be less 30 than the extension of the rubber thread before it reaches its elastic limit and consequently further strain on the rubber thread is taken by the covers which are inextensible and further stretch is prevented. The cover 35 threads 12 and 14 must break before the rubber thread can be ruptured. The covers 16 and 18 also assist in limiting the stress of the covered rubber fabric by engaging and compressing the rubber thread and thereby 40 offering resistance to its stretch. When the covered thread is unduly stressed, the cover threads usually break one at a time so that the load is thrown upon the successive covers, especially the outer covers 16 and 18 with 45 the rubber thread stretching somewhat when the load is transferred to another cover, thereby considerably relieving the load on the thread.

The cover elastic thread herein described, 50 in addition to having a limited stretch and an initially low tension, is further characterized by lying flat or straight and is free from kinks or a cork-screw effect and is similar in appearance to the usual unrestricted-stretch covered elastic thread.

I claim:

1. A short-stretch low-tension covered elastic thread having an elastic rubber thread characterized by being under but 60 little tension when in repose and having a plurality of spirally-wound superimposed covers thereon applied one entirely outside the other, the inner covers having a greater pitch than the outermost cover.

65 2. A short-stretch covered elastic thread

consisting of an elastic rubber thread having a plurality of cover threads spirally wound thereon, one entirely outside and free from interlocking connection with the other cover threads, at least one of said cover 70 threads characterized by becoming substantially straightened at a point well within the elastic limit of the rubber thread when the covered elastic thread is stretched, whereby to limit the stretch of the rubber thread. 75

3. A short-stretch covered elastic thread consisting of an elastic rubber thread having a plurality of covers spirally wound thereon in opposite directions, and any one cover being entirely outside and free from 80 interlocking connection with a lower cover, at least two of said covers cooperating to compress the rubber thread when the covered thread is stretched thereby to limit the amount of stretch, the inner covers being applied in such open spirals as to expose the unextended rubber thread, and the outer cover being applied in such close spiral as to conceal the rubber thread when unextended and also when extended. 90

4. A covered elastic thread consisting of an elastic rubber thread having two superimposed covers spirally wound in opposite directions thereon in a relatively long-pitched open spiral one entirely outside the 95 other and another cover wound upon said first two covers with a shorter-pitched spiral.

5. A covered elastic thread consisting of an elastic rubber thread having two superimposed covers spirally wound in opposite 100 directions thereon in a relatively long-pitched open spiral one entirely outside the other, a third cover spirally wound upon said first two covers in a shorter-pitched open spiral and a fourth multi-ended cover 105 spirally wound upon said rubber and over the aforesaid covers, the winding-pitch of certain of said covers being different.

6. A covered elastic thread consisting of an elastic rubber thread having an outside 110 cover and a plurality of inner covers successively-operable to limit the stretch of the thread, said inner covers characterized by permitting the rubber thread to stretch somewhat upon the breaking of one of said covers whereby to apply the tension upon another of said covers. 115

7. A restricted-stretch covered elastic thread consisting of an elastic thread having a plurality of independent covers 120 consisting of inelastic threads wound in superimposed and alternately reversed order in opposite directions one entirely outside the other on said elastic thread, said covers characterized by having convolutions of differing pitches, and differing numbers of ends. 125

In testimony whereof, I have signed my name to this specification.

RAY C. HALL.
